UNITED STATES PATENT OFFICE.

HARRY D. JOHNSON, JR., OF SOUTH BEND, INDIANA, ASSIGNOR TO THE STUDEBAKER CORPORATION, OF SOUTH BEND, INDIANA, A CORPORATION OF NEW JERSEY.

POWER-FLUSHER.

1,179,323.

Specification of Letters Patent. Patented Apr. 11, 1916.

Application filed August 15, 1913. Serial No. 784,861.

To all whom it may concern:

Be it known that I, HARRY DISBROW JOHNSON, Jr., a citizen of the United States, residing at South Bend, in the county of 5 St. Joseph and State of Indiana, have invented certain new and useful Improvements in Power-Flushers, of which the following is a full, clear, and exact description, such as will enable others skilled in the art to 10 which it appertains to make and use the same.

This invention relates to distributing apparatus for roadways, and with regard to certain more specific features, to street flushing apparatus.

One of the objects of the invention is the provision of a practical portable street flusher wherein an effective and efficient character of liquid jet may be maintained.

20 Another object of the invention is the provision of a simple and efficient portable device of the character referred to wherein with a uniform discharge of liquid may be effected irrespective of the gravity head in 25 the reservoir.

Another object is the provision of a practical portable flusher wherewith a full and constant discharge of liquid may be effected for all positions of the discharge nozzles.

30 Other objects and advantages will be in part obvious and in part pointed out herein-after.

The invention accordingly consists in the features of construction, combinations of 35 elements and arrangement of parts which will be exemplified in the construction hereinafter set forth, and the scope of the application of which will be indicated in the following claims.

40 In the accompanying drawings showing one of various possible embodiments of the invention, and wherein similar reference characters refer to similar parts throughout the several views, Figure 1 is a side elevation of the apparatus; Fig. 2 is a plan view of a portion of the apparatus, the reservoir being removed to disclose other parts more clearly; Fig. 3 is a detail view showing a nozzle in sectional elevation; and Fig. 4 is 45 a plan view of the nozzle partly in section.

50 It may here be noted that in certain prior forms of apparatus of the character generally referred to, inefficient flushing or application of the liquid to the street or road-

way has resulted for the reason, among 55 others, that the character of the jet of liquid has not been maintained. In such prior forms, as the liquid is discharged, the force of the jet correspondingly decreases. As upon the force of the jet mainly depends its 60 efficiency in scouring or displacing the material operated upon, it is evident that its efficiency in this respect decreases as the force of the jet lessens. Furthermore, when the jet is directed laterally, or at an angle 65 to the direction of its natural flow under the influence of gravity, not only does the scouring action of the jet decrease with decrease of head, but the distribution of the liquid is as well materially and deleteriously affected. 70 This latter effect is especially noticeable in that form of apparatus of the character referred to wherein the jet is directed laterally in a thin sheet and especially where the upper edge of the jet flows from the nozzle 75 in a substantially horizontal direction. In the latter instance, as the head decreases, the distance to which the water is projected also decreases, so that while at the beginning of an operation a certain width of pavement 80 or roadway may be cleaned, the application of the liquid gradually decreases in width as the available pressure lessens, so that when the latter has materially decreased, the liquid will be applied only to a fraction of 85 the width covered thereby under initial conditions, and even this area is ineffectively treated. Under these latter circumstances it is frequently necessary to operate a second time upon a substantial portion of the roadway 90 in order to apply the liquid to the full width and length of the roadway, and thus not only additional time is required but that portion of the pavement or roadway which has been previously treated with a liquid is 95 treated a second time, with consequent waste of liquid. It will be apparent that the present invention avoids, among others, the objections above noted.

Referring now more particularly to the 100 drawings, the numeral 1 indicates a reservoir, tank or other receptacle for the liquid, provided with an opening 2 for the introduction of the liquid. The opening 2 may be provided with a cover, if desired. The 105 liquid used in so far as the broader features of the invention are concerned, may be any liquid comporting with the results desired,

such as water where flushing or temporary laying of the dust are desired, oil where improvement of the roadway and a permanent laying of the dust are required. The reservoir 1 is designed to be moved over or adjacent the roadway or pavement to which the liquid is to be applied, and for this purpose may be provided with any efficient form of running gear capable of rendering the reservoir portable, but preferably is mounted upon a wheeled carrier provided with draft gear to which horses may be attached in the manner usually employed in street flushing apparatus.

15 There are provided a seat 3 and a platform 4 which, as shown, are suitably supported at the front of the reservoir 1. On account of the portable character of the apparatus and the operation thereof in streets and roadways, the reservoir 1 may be said to be self-contained, that is to say, it is provided with a predetermined amount of liquid at the beginning of an operation, said liquid is discharged as the reservoir passes 20 along the roadway and then said reservoir is refilled prior to another operation.

25 The carrier preferably comprises parallel longitudinal members 5 spaced apart and braced by end cross-pieces 6 and 7, the latter of which may serve for the connection of a fifth wheel as is customary. Intermediate cross-pieces 8 coöperate with the cross-piece 7 in supporting the reservoir 1 on the carrier, and the carrier is provided with devices for supporting the wheels as is customary upon a wheeled vehicle. An opening 9 is provided at such a point of the reservoir 1 as will permit the contents of the reservoir to flow therethrough by gravity, said opening being preferably located in the bottom of the reservoir, and a conduit leads from the opening 9 to the discharge nozzles of the apparatus, said conduit preferably comprising sections for a 30 purpose hereinafter explained.

35 In the present embodiment the conduit comprises a curved nipple 10 connected to the reservoir and leading directly from the opening 9, a flexible section 11 connected to the nipple 10 and leading to the inlet of a pump 12 supported upon a platform or frame 13 located beneath the reservoir preferably at the rear thereof. A second curved nipple 14 leads from the outlet of the pump 12 and a second flexible section 15 is connected to the nipple 14 and to a section 16 relatively stationarily supported, as by brackets 17 depending from the longitudinal members 5, which latter section is connected to the discharge end or nozzle 18, from which the liquid is discharged onto the roadway. From the outlet of the pump, duplicate sections 16 are provided so that the elements of the conduit through which the pump discharges comprise branches leading to oppo-

site sides of the carrier, as will be apparent from the drawings.

The pump 12 is preferably a power pump and while the invention, viewed in some aspects, might contemplate the employment of any efficient form of pump, the invention viewed in its special relationship involving the employment of a self-contained reservoir, utilizes a form of pump calculated to force the liquid therefrom through the nozzles at a substantially uniform pressure and rate, and it is found that a rotary, or centrifugal, pump positioned intermediate the inlet and discharge ends of the conduit accomplishes the desired results in an efficient and practical manner. The particular form of pump referred to is adapted to readily receive the liquid flowing from the reservoir by gravity and to cause the discharge of liquid through the nozzles at a substantially uniform pressure and rate irrespective of the pressure in the reservoir or the depth of the liquid therein. The driving mechanism for the pump 12 may comprise any suitable form of motor, but in view of the special uses of the apparatus and the self-contained character of the reservoir 1, an internal combustion engine 19 having a speed governor 20 is employed. Said engine is mounted upon the platform 13, its crank shaft 21 being located slightly to one side of the central longitudinal line of the carrier and power is positively transmitted from said engine to the pump shaft 22 by any efficient mechanism as gearing or, as illustrated, by means of a sprocket chain 23 engaging sprocket wheels on the engine shaft and pump shaft, respectively. The pump 12 is mounted upon the frame 13 by a substantial support or standard and the projecting end of the pump shaft 22 is supported in a bracket 24 also mounted upon the frame 13. The engine 19 is provided with a water jacket for cooling purposes and this jacket is properly connected by the flexible pipes 25 and 26 to an auxiliary water-tank 27, in the present embodiment formed between the rear end of the reservoir and a partition 28 separating the main body of liquid from that in the auxiliary reservoir, the liquid in the auxiliary reservoir being thus adapted to circulate through the jacket and operate as a cooling element.

30 In the present embodiment the reservoir is mounted directly upon the carrier without the interposition of any resilient supporting means. The discharge nozzles of the conduit if permitted to vibrate, might cause a variation in the application of the liquid to the roadway, which variation would not be uniform owing to the different characters of roadways, and hence the discharge nozzles are so mounted on the apparatus as to maintain a stationary, as distinguished from a vibratory, condition relative to the 35

carrier or reservoir. It will be apparent that this stationary condition of the nozzles is accomplished in the present embodiment by mounting said nozzles on the carrier frame, which latter is supported upon the running gear without the interposition of any resilient means, such as springs, etc.

Although it may be permissible to mount the nozzles in stationary relation to the carrier, as described, it is undesirable to so mount the pump and the engine owing to the fact that the jolts and jars which would be caused in the latter would tend to their deterioration or interfere with their operation. Hence both the engine and the pump are yieldingly supported, preferably, as in the present embodiment, by the provision of longitudinally disposed bow-springs 29 fastened intermediate their ends to brackets 30 bolted to the members 5. The frame 13 may, as illustrated, be of skeleton form for the purpose of lightness and its corners are provided with upstanding members 31 connected in pairs to the opposite ends of the 25 springs 29 by means of links 32 pivoted to said springs and to the uprights 31, the axes of the pivots being preferably transversely disposed relative to the direction of the movement of the carrier. By this construction both the pump and the engine are resiliently supported and permit vertical oscillation relative to the carrier which is desirable when the apparatus traverses a rough roadway, and a slight longitudinal 35 oscillation may also be permitted. It will be observed, however, that any substantial lateral oscillation of the engine and motor is prevented by the construction described. Preferably the engine is mounted beyond 40 the rear end of the reservoir, the members 5 also extending beyond said rear end to provide means of attachment for the uprights 31. A fuel supply tank 33 is removably held at the upper rear portion of 45 the reservoir 1 by means of a bracket arm 34 on the reservoir, and a similar arm on the supply tank bolted to the first-mentioned arm. To the lower portion of the tank 33, at 35, is pivoted a hood 36, which 50 in its lower position serves to screen the engine and adjacent parts from the weather, dust, etc. A fuel pipe 37 connects the tank 33 with the carburetor of the engine.

As, in the present embodiment, both the 55 nipple 10 and the nozzles 18 are stationary relative to the reservoir and the carrier, a loose connection is provided between the power pump and the conduit in order to accommodate relative bodily movements of the pump. The preferred form comprises the conduit sections 11 and 15 which may be flexible hose of sufficient strength to withstand the pressure, suitable packing being employed to form a liquid-tight joint with the adjoining sections of the conduit. It

is evident that the bodily movement of the pump is thus readily permitted and at the same time said sections 11 and 15 more or less serve as shock absorbers to prevent undue vibrations of the pump and the parts 70 fastened thereto.

Inasmuch as the discharge ends or nozzles of the conduits of the present embodiment are similar in form, a description of one will suffice for both. Each stationary section 16 is provided with a valve-box 38 forming a part of the conduit and by means of which said conduit is connected to the carrier through the bracket 17. A valve in each box serves to control the supply of 80 liquid to the nozzles 18, each valve being provided with a stem 39 connected by bell-crank and connecting rods to a hand-lever 40 fulcrumed on the carrier and in convenient position to be operated from the 85 seat 3. The conduits are continued from the valve-box in pipes 41 to which latter the discharge nozzles are universally connected so that the latter may be adjusted to discharge the water in any desired direction. In the present instance the nozzle 18 is swiveled to an angular pipe section 42, which latter in turn is swiveled to a second angular pipe section 43 in turn swiveled upon the pipe 41. Each swivel 90 joint comprises clamping elements as 44 and 45 which may be tightened by means of the bolts 46, it being thus possible to adjust the nozzle 18 to any desired position. Each nozzle 18 is provided with an outwardly 130 flaring passageway, said passageway preferably terminating in a narrow slot or opening adapted to eject the water in a flat sheet.

47 indicates a magneto suitably geared to 105 the engine and adapted to furnish current for the igniters of the cylinders, a suitable timer and wiring being employed as is usual in internal combustion engines. Any suitable form of switch may be interposed 110 in the ignition circuit, a hand-operated switch being conventionally indicated at 50, within reach of the operator on the seat 3.

The numerals 51 indicate wires of the 115 ignition circuit leading to contacts 52 and 53, respectively.

The speed governor of the engine may be of any approved type, a common ball governor being conventionally illustrated as at 120, and said governor may be mounted on a stub shaft 54 projecting from the cylinder, and driven from the crank shaft by intermeshing gears 55 and 56. The governor is connected to operate a throttle valve 57 located in the intake pipe leading from the carburetor to the engine, and is adapted to close said valve more or less when the engine exceeds a predetermined speed. An additional throttle valve 58 is also located 125 in said intake pipe between the carburetor 130 and

and the engine, and nearer the carburetor than the governor-controlled throttle valve, and said valve 58 is adapted to be opened and closed by the operator on the seat 3, 5 through the instrumentality of a rock shaft 59, having an arm 60 connected to an arm on the valve 58 by a link 61. Another arm 62 on the rock shaft 59 is pivoted to a foot-rod 63, extending through the foot-platform 4, said rod 63 having a rack 64 adapted to engage a suitable tooth on the platform 4, and restrain upward movement of said rod, thereby keeping the throttle valve 58 open, in a variety of adjusted positions. A spring 10 65 is connected to the foot-rod 63 and to the platform 4, and exerts its tension to raise said foot-rod.

Although the reservoir of the apparatus may be filled from a proper source by introducing the liquid through the opening 2, it often happens that a suitable head of liquid is not available for such purpose, and the present apparatus provides a means for filling the tank independently of a source 20 having a sufficient head. To the latter end, the nipple 12' forming part of the conduit leading the liquid from the tank 1 to the pump 12, has a laterally-extending tubular portion 70 which is coupled to a pipe 71 25 supported in brackets or stirrups 72 depending from the platform 13, the pipe 71 extending to substantially the rear end of the machine. To the open rear end of the pipe 71 may be coupled one end of a flexible 30 hose 73, the other end of said hose being adapted to be inserted in a suitable body of liquid, such as a convenient stream or other supply of liquid. In the pipe 71 is provided a check valve 74 opening toward 35 the pump 12.

Numerals 75 indicates a by-pass pipe between the conduit leading from the reservoir 1 to the pump and the discharge conduit of the pump, and 76 is a hand operated 40 valve adapted to open or close the by-pass. Numeral 77 is a second hand operated valve 45 adapted to open and close passage through a portion of the conduit leading from tank 1 to pump 12, this latter valve being located 50 between the by-pass and the point where pipe 71 communicates with nipple 12'. In order to fill the tank by means of the pump, the valve 76 is opened and the valve 77 closed, whereupon the operation of the 55 pump will cause liquid to be drawn thereinto through hose 73, pipe 71, and nipple portion 70, and discharged through nipple 14 and by way of the by-pass 75 into the tank. The tank having been filled, the valve 60 76 is closed and the valve 77 opened and the flusher is ready to operate, the check valve 74 operating to automatically close the pipe 71. Should it be desired to utilize the flusher without its power features, the valve 65 77 may be closed and the valve 76 opened,

whereupon the liquid in the tank will flow directly to the nozzles without being required to pass through the pump. As it is desirable to employ liquid free from sediment which might tend to clog the passage- 70 ways of the apparatus, the pipe 71 is provided with any efficient form of strainer 78 to remove sediment such as sand, etc., from the liquid supplied to the reservoir.

The operation of the apparatus will be 75 apparent from the above but may be briefly further explained. The reservoir 1 is filled with the liquid to be dispensed, let us say water, the proper valves being closed, and the engine is started as by turning over 80 the crank 48. The apparatus may then be drawn to the place in which it is to be used, whereupon the driver operates the lever or levers and the water will be discharged in a flat sheet and in any desired direction, preferably in a generally forward and downward direction with the plane of the slot of each nozzle at an angle of about 45° to the horizontal, the nozzles being turned also slightly outwardly 85 so as to direct the sheet of water at about an angle of 45° to the line of draft. The engine being provided with a speed governor runs at constant speed, and the power of the engine is designed to be ample to 90 discharge the water at the desired pressure when the water in the reservoir is low, or the reservoir practically empty, so that the size of the discharge sheet of liquid is maintained substantially uniform. When the 100 reservoir is full the gravity head tends to aid the engine, and as the head decreases the engine keeps up the water pressure at the nozzles to the original uniform pressure desired. The pump may be of such design 105 as to permit the same to run under the power of the engine though the valves 38 be closed, so that in passing parts of the roadway or objects not to be operated upon the discharge may be shut off without causing the engine to stop.

It will thus be perceived that by the foregoing is produced a practical apparatus capable of accomplishing the objects hereinbefore referred to, and also capable of fulfilling the vicissitudes of practice. Should the roadway over which the apparatus operates be such as to interfere with the efficient operation of the governor 20, or even to put it out of operation, as, for instance, by disconnecting it from the throttle valve 57, the driver has at hand the throttle valve 58 which may be manipulated to vary the power of the engine, the driver having only to depress the rod 63 to increase the amount of fuel sucked into the engine or to permit said rod to rise under the influence of the spring 65 in order to decrease the amount of fuel supplied. In this wise the impelling force of the pump may be varied, and a force 115 120 125 130

attained to keep up the pressure of discharge at the nozzles.

If desired, a suitable form of friction clutch may be interposed in the engine shaft, as is usual in internal combustion motors. It is also to be understood that the apparatus may be provided with the usual accessories, such as a pressure gage, brakes, etc., when desirable. It is furthermore to be noted that the internal combustion engine may be employed as a motor to drive the vehicle, by the provision of suitable driving connections or gearing between the crank shaft of the engine and the wheels of the vehicle, a suitable hand controlled clutch being employed to couple and uncouple the engine with the wheels of the vehicle.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. A portable liquid distributing apparatus comprising, in combination, a nozzle, a conduit adapted to lead liquid to said nozzle, means adapted to supply liquid to said conduit with a pressure which decreases during the operation of the apparatus, and means comprising a motor and a centrifugal pump operatively connected to said motor, said pump being operatively related to said conduit and adapted to impel liquid therein, and said motor being adapted to operate said pump with an increasing force during the operation of the apparatus, whereby the force of discharge from said nozzle is maintained substantially uniform.

2. A portable liquid distributing apparatus comprising, in combination, a nozzle, a conduit adapted to lead liquid to said nozzle, means adapted to supply liquid to said conduit with a pressure which decreases during the operation of the apparatus, an internal combustion engine, a centrifugal pump operatively connected to said engine, said pump being operatively related to said conduit and adapted to impel liquid therein, and means adapted to cause said engine to operate said pump with an increasing force during the operation of the apparatus, whereby the force of discharge from said nozzle is maintained substantially uniform.

3. A portable liquid distributing apparatus comprising, in combination, a nozzle, a conduit adapted to lead liquid to said nozzle, a reservoir disposed to supply said conduit with liquid by gravity, an internal combustion engine, a centrifugal pump opera-

tively connected to said engine, said pump being operatively related to said conduit and adapted to impel liquid therein, and means adapted to cause said engine to operate said pump with an increasing force during the operation of the apparatus, whereby the force of discharge from said nozzle is maintained substantially uniform.

4. A portable liquid distributing apparatus comprising, in combination, a nozzle having a passageway terminating in a narrow slot and adapted to be disposed to discharge liquid in a direction at an angle to the direction of the force of gravity, a conduit adapted to lead liquid to said nozzle, means adapted to supply liquid to said conduit with a pressure which decreases during the operation of the apparatus, a motor, a centrifugal pump operatively connected to said engine, said pump being operatively related to said conduit and adapted to impel liquid therein, and means adapted to cause said motor to operate said pump with an increasing force during the operation of the apparatus whereby the size of the discharging sheet of liquid is maintained substantially uniform.

5. A portable liquid distributing apparatus comprising, in combination, a nozzle having a flaring passageway terminating in a narrow slot adapted to be disposed to discharge liquid in a direction at an angle to the direction of the force of gravity, a conduit adapted to lead liquid to said nozzle, a reservoir disposed to supply said conduit with liquid by gravity, an internal combustion engine, a constant speed governor for said engine, and a centrifugal pump operatively connected to said engine and operatively related to said conduit to impel liquid therein, whereby said pump operates with an increasing force during the operation of the apparatus and the force of discharge from said nozzle is maintained substantially uniform.

6. In an apparatus of the character described, in combination, a carrier, supporting wheels therefor, a liquid reservoir supported by the carrier, longitudinally disposed springs mounted on the carrier on opposite sides thereof, a supporting frame, links connecting said frame to said springs whereby a longitudinal movement of said frame relative to the carrier is permitted, a power pump carried by said frame, a conduit leading from the bottom portion of the reservoir to the inlet of said pump and means adapted to control the discharge of liquid from the reservoir through said conduits.

7. In an apparatus of the character described, in combination, a carrier, supporting wheels therefor, a liquid reservoir supported by the carrier, longitudinally disposed springs mounted on the carrier on

- opposite sides thereof, a supporting frame, links connecting said frame to said springs whereby a longitudinal movement of said frame relative to the carrier is permitted, a power pump carried by said frame, a conduit comprising a connection leading from the bottom portion of the reservoir to the inlet of said pump, adapted to permit vertical and longitudinal play, a conduit comprising a connection leading from the outlet of said pump adapted to permit vertical and longitudinal play, and means adapted to control the discharge of liquid from the reservoir through said conduits.
8. In an apparatus of the character described, in combination, a carrier, supporting wheels therefor, a liquid reservoir supported by the carrier, springs mounted on the carrier on opposite sides thereof, a supporting frame, links connecting said frame to said springs whereby a movement of said frame relative to the carrier is permitted, a power pump carried by said frame, a conduit leading from the reservoir to the inlet of said pump, and means adapted to control the discharge of liquid from the reservoir through said conduit.
9. A portable liquid distributing apparatus comprising, in combination, a nozzle, a conduit adapted to lead liquid to said nozzle, means adapted to supply liquid to said conduit with a pressure which decreases during operation of the apparatus, a manually operable valve adapted to control flow through said nozzle, an internal combustion engine, a centrifugal pump operatively connected to said engine, said pump being operatively related to said conduit and adapted to impel liquid therein, and means whereby the impelling force of the pump

may be varied during operation of the apparatus.

10. A portable liquid distributing apparatus comprising, in combination, a nozzle adapted to discharge liquid in sheet form, a conduit adapted to lead liquid to said nozzle, means adapted to supply liquid to said conduit with a pressure which decreases during operation of the apparatus, a manually operable valve adapted to control flow through said nozzle, an internal combustion engine, a centrifugal pump operatively connected to said engine, said pump being operatively related to said conduit and adapted to impel liquid therein, and means whereby the power of said engine may be increased, thereby increasing the impelling force of said pump.

11. A portable liquid distributing apparatus comprising, in combination, a nozzle, a conduit adapted to lead liquid to said nozzle, means adapted to supply liquid to said conduit with a pressure which decreases during operation of the apparatus, a manually operable valve adapted to control flow through said nozzle, an internal combustion engine, a centrifugal pump operatively connected to said engine, said pump being operatively related to said conduit and adapted to impel liquid therein, manually operable means for varying the supply of fuel to said engine at will, and automatically operating means adapted to maintain substantially uniform speed of said pump.

In testimony whereof I affix my signature, in the presence of two witnesses.
